UNITED STATES PATENT OFFICE

91,152

DESIGN FOR A WASHING MACHINE WRINGER FRAME

Carl C. Weisbrod, Newton, Iowa, assignor to One
Minute Washer Company, Newton, Iowa, a cor-
poration of Iowa

Application September 18, 1933. Serial No. 49,287

Term of patent 14 years

To all whom it may concern:

Be it known that I, CARL C. WEISBROD, a citizen of the United States, and a resident of Newton, in the county of Jasper and State of Iowa, have invented a new, original, and ornamental Design for a Washing Machine Wringer Frame, of which the following is a specification, reference being had to the accompanying drawing, forming part thereof.

Figure 1 is a perspective view of a washing machine wringer frame, showing my new design when viewed from the inner end thereof.

Figure 2 is a front view of the same; and
Figure 3 is an end elevation of the opposite or
outer end of the frame as shown in Figure 1.

I claim:

The ornamental design for a washing machine
wringer frame, substantially as shown and de-
scribed.

Des Moines, Iowa, September 14, 1933.

CARL C. WEISBROD.
